CLAIM

The ornamental design for an upright vacuum cleaner as shown and described.

DESCRIPTION

FIG. 1 is a perspective view of an upright vacuum cleaner showing our new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

Broken lines and shaded areas within broken lines form no part of the claimed design.

1 Claim, 7 Drawing Sheets
